(57) **CLAIM**

The ornamental design for a combined cushion and frame module for patient interface, as shown and described.

DESCRIPTION

FIG. 1 is a front perspective view of a combined cushion and frame module for patient interface according to a first embodiment of our new design;

FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof;

FIG. 8 is a rear perspective view thereof;

FIG. 9 is a front perspective view of a combined cushion and frame module for patient interface according to a second embodiment of our new design;

FIG. 10 is a front view thereof;

FIG. 11 is a rear view thereof;

FIG. 12 is a top view thereof;

FIG. 13 is a bottom view thereof;

FIG. 14 is a right side view thereof;

FIG. 15 is a left side view thereof; and,

FIG. 16 is a rear perspective view thereof.

The broken lines in the drawings illustrate portions of the combined cushion and frame module for patient interface which form no part of the claimed design.

Line shading and stippling have been used in the drawings to indicate a contrast in appearance.
